(57) CLAIM

The ornamental design for a set of orthodontic appliances, as shown and described.

DESCRIPTION

FIG. 1 is a perspective view of a first embodiment of a set of orthodontic appliances showing my new design;

FIG. 2 is a perspective view of a second embodiment of a set of orthodontic appliances showing my new design;

FIG. 3 is a front view of the set of orthodontic appliances in FIG. 1;

FIG. 4 is a rear view of the set of orthodontic appliances in FIG. 1;

FIG. 5 is a left side view of the set of orthodontic appliances in FIG. 1;

FIG. 6 is a right side view of the set of orthodontic appliances in FIG. 1;

FIG. 7 is a top plan view of the set of orthodontic appliances in FIG. 1;

FIG. 8 is a bottom plan view of the set of orthodontic appliances in FIG. 1;

FIG. 9 is a front view of the set of orthodontic appliances in FIG. 2;

FIG. 10 is a rear view of the set of orthodontic appliances in FIG. 2;

FIG. 11 is a left side view of the set of orthodontic appliances in FIG. 2;

FIG. 12 is a right side view of the set of orthodontic appliances in FIG. 2;

FIG. 13 is a top plan view of the set of orthodontic appliances in FIG. 2; and,

FIG. 14 is a bottom plan view of the set of orthodontic appliances in FIG. 2.

The broken lines in the drawings depict portions of the set of orthodontic appliances that form no part of the claimed design.

1 Claim, 14 Drawing Sheets
